United States Patent Office

Des. 201,072
Patented May 11, 1965

201,072

PARTITION

Arnon Hiller, 82—46 Lefferts Blvd.,
Kew Gardens 15, N.Y.

Filed July 27, 1964, Ser. No. 31,014

Term of patent 14 years

(Cl. D13—1)

FIG. 1.

FIG. 2.

FIG. 3.

The center of the partition is broken away in FIGS. 1 and 3 to indicate an article of indeterminate height.

I claim:

The ornamental design for a partition, as shown and described.
